COMBINED MULTIPLE PAINT CONTAINER AND MIXING TRAY FOR ARTISTS

Raymond A. Irwin and Joseph F. Sanlader, Manitowoc, Wis., assignors to Kaysun, Inc., Manitowoc, Wis., a corporation of Wisconsin

Application June 4, 1959, Serial No. 56,206

Term of patent 14 years

(Cl. D58—26)

Fig. 1.

Fig. 2.

Fig. 3.

Fig. 4.

We claim:

The ornamental design for a combined multiple paint container and mixing tray for artists, as shown.
